UNITED STATES PATENT OFFICE.

EUGENE L. MCGUIRE, OF DENNISON, OHIO, ASSIGNOR OF ONE-HALF TO ALEXANDER SALES, OF DENNISON, OHIO.

TOP FOR DRINKING BOTTLES.

Application filed April 4, 1921. Serial No. 458,256.

To all whom it may concern:

Be it known that I, EUGENE L. MCGUIRE, a citizen of the United States, residing at Dennison, in the county of Tuscarawas and 5 State of Ohio, have invented a new and useful Top for Drinking Bottles, of which the following is a specification.

This invention relates to sanitary mouth pieces to be used in connection with bottle 10 mouths whereby a person may drink from a bottle, eliminating the necessity of placing his lips on the mouth piece of the bottle.

An object of the invention is to provide a device of this character which may be 15 readily and easily positioned over the mouth of a bottle when the cap or stopper has been removed, thereby guarding the user against cutting his lips on the bottle mouth, should the same become broken.

20 A still further object of the invention is to provide a protector formed of flexible material to permit the protector to grip the mouth piece of a bottle to securely hold the mouth piece in position.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

35 Referring to the drawing:—

Figure 1 is a side elevational view of a bottle mouth supplied with a protector constructed in accordance with the present invention, the protector being partly broken 40 away to illustrate the securing flange thereof.

Figure 2 is a side elevational view of a bottle mouth supplied with a protector, the same being taken at right angles to Figure 1 illustrating the securing fingers of the 45 protector.

Figure 3 is a plan view of the same.

Figure 4 is a perspective view of the protector.

50 Referring to the drawing in detail, the

reference character 5 designates a bottle neck having the usual mouth indicated at 6, the bottle neck being provided with the usual reinforcing enlargements. The protector forming the subject matter of the present invention is stamped from card board or heavy paper material, and is formed with relatively long neck engaging fingers 7, there being provided shoulders 8 formed on the fingers for engaging with the enlargement 9 of the bottle mouth, to restrict movement of the protector with respect to the bottle mouth when the same is applied.

The body portion 10 forms a part of the mouth piece and is provided with an inwardly extending flange 11 adapted to closely engage the extreme edge of the mouth piece of a bottle, to cover the edge of the bottle, to protect the user against rough or sharp edges. To further enhance the utility of the device, it may be found desirable to paraffine or water-proof the protector.

In the use of the device, a bottle containing a beverage, may be opened in the usual manner, and the protector applied over the 75 mouth of the bottle, whereupon the bottle may be placed to the lips of the user, to drink the contents of the bottle.

Having thus described the invention, what is claimed as new is:—

80 A mouth piece for bottles having enlargements, comprising a body portion formed of flexible material and having an inwardly extending flange adapted to embrace the mouth of a bottle, integral fingers formed 85 on the mouth piece and adapted to embrace the neck of the bottle, said fingers having shoulders cooperating with the enlargement of the bottom to restrict movement of the mouth piece with respect to the bottle, and said fingers adapted to grip the neck of the bottle.

90 In testimony that I claim the foregoing as my own, I have hereto affixed my signature in the presence of two witnesses.

EUGENE L. MCGUIRE.

Witnesses:

MARGARET LIVINGSTON,
MARY M. FERRELL.
